UNITED STATES PATENT OFFICE.

SAMUEL PRICE STEVENSON, OF CHESTER, PENNSYLVANIA.

DOOR-FASTENER.

No. 872,470.

Specification of Letters Patent.

Patented Dec. 3, 1907.

Application filed April 13, 1905. Serial No. 255,106.

To all whom it may concern:

Be it known that I, SAMUEL PRICE STEVENSON, of Chester, in the county of Delaware and State of Pennsylvania, have invented certain new and useful Improvements in Door-Fasteners, whereof the following is a specification, reference being had to the accompanying drawings.

The object of my invention is to provide a fastener which shall meet the requirements of such doors as are used upon refrigerating apartments and the like, where it is necessary to force the door into close contact with the margin of the doorway, a compressible packing being ordinarily employed at this region. The doors and doorways of such structures are subject to variations of thickness and position, due to swelling shrinking and twisting, so that for satisfactory use, the door fastener must be able to accommodate itself to the various changes and yet be strong and capable of very firm action.

In said drawings, Figure I, represents a front elevation of the fastener, showing the adjacent portion of the door. Fig. II, is a longitudinal section through the fastener, and adjacent portion of the door, taken on the line II, II, in Fig. I.

In the accompanying drawings, 1, represents a hollow door of the ordinary type employed in such structures, having a filling of nonconducting material, and 2, represents a packing strip of compressible and preferably elastic material applied around the margin of the door, so as to form a close joint with the surface of the doorway. The base-plate 3, of the fastener is secured to the door by means of screws and is provided with guides 4, 4, for the sliding bolt 5, formed of a wide and flat elastic strip of metal whose front extremity 6, is curved inwardly. The bolt 5, is attached by a screw pin 7, to one end of a link 8, the other end of said link being provided with a hole which engages with a stud 9, upon an oval plate 10. Said plate 10, has a second stud 11, diametrically opposite to the stud 9, and the inner ends of said two studs are secured to a second oval plate 12, which constitutes the head of a spindle 22, extending through the door. The plate 10, has a squared projection 13, adapted to receive a lever-handle 14, and the spindle 22, is provided with a similar squared end 15, upon the other side of the door adapted to engage the lever-handle 16.

The bearings for the spindle 22, are provided in the base plate 3, and the plate 24, secured upon the opposite side of the door. Intermediate between these bearing points the spindle 22, is surrounded by an elongated packing 25, of such absorbent character as is adapted to be maintained in a greased condition, felt being preferably used for the purpose. This packing is maintained in position around the spindle by means of a thin sleeve 26, which is mounted in a proper recess formed in the wood work of the door between the plates 3, and 24. The purpose of this packing is to prevent the ingress of moisture and its congelation upon the working parts in such a hard condition as might impede the free manipulation of the bolt.

Rests 17, and 18, are secured upon the opposite sides of the door in the proper relation to receive the handles 14, and 16, when turned into the extreme position, corresponding with the locking of the bolt. The doorway is provided with a hasp 19, having a freely mounted roller 23, arranged in such relation to the plane of movement of the bolt, that the inwardly curved front end 6, thereof, when projected, shall pass inside said roller and, by its engagement therewith, be sprung inwards, or towards the door-way, thus tending to press the door tightly in its closed position. Rotation of either the handle 14, or the handle 16, to the right in Fig. I, will actuate the link 8, and withdraw the bolt from contact with the hasp roller, the movement in this direction being limited by contact between the stud 11, and the under side of the link 8, at which point further rotation of the oval plates 10, and 12, will be arrested. In this position, the handles will have been thrown some distance past the vertical, and hence the device will rest in the open position until intentionally shifted. Obviously, when the bolt has been shot for closing the door, the two handles will be supported in the rests 17, and 18, and hence be safe against any other than intentional displacement. Holes 20, and 21, may be formed in the respective handles and rests, so as to permit them to be secured by means of a pad-lock.

Having thus described my invention, I claim:

1. The combination of a bolt in a direction transversely of its length, means for shifting

the same, and a hasp having a roller whose engaging surface is inside the plane of movement of the bolt, whereby when the bolt is protruded, its front end is sprung towards the 5 doorway.

2. The combination of a bolt in a direction transversely of its length; a link; a rotatable plate having studs, one of which is connected with said link and the other of which is adapted to engage with the surface of said link in one extreme position; a spindle for actuating said plate; a handle for said spindle; and a hasp having a roller adapted to engage the front end of said bolt.

15 3. In a securing device for doors of refrigerating apartments, the combination

with a door; of a sliding bolt mounted upon the inner face of said door; an actuating spindle for said bolt, which spindle passes entirely through the door; an elongated greased packing of absorbent material surrounding said spindle; and a sleeve surrounding said packing.

In witness whereof, I have hereunto signed my name, at Philadelphia, in the State of Pennsylvania, this eleventh day of April, 1905.

SAMUEL PRICE STEVENSON.
